(57) **CLAIM**

The ornamental design for net pocket, as shown and described.

DESCRIPTION

FIG. 1 is an isometric view of net pocket showing my new design;
 FIG. 2 is a front elevational view of FIG. 1;
 FIG. 3 is a rear elevational view of FIG. 1;
 FIG. 4 is a right elevational view of FIG. 1;
 FIG. 5 is a left side elevational view of FIG. 1;
 FIG. 6 is a top plan view of FIG. 1;
 FIG. 7 is a bottom plan view of FIG. 1; and,
 FIG. 8 is an isometric operational view of net pocket.
 The broken lines are included for the purpose of illustrating features of the net pocket that form no part of the claimed design.

1 Claim, 4 Drawing Sheets(56)
